(57) **CLAIM**

The ornamental design for a smart charger with built-in connector, as shown and described.

DESCRIPTION

FIG. 1 is a top view of a smart charger with built-in connector;

FIG. 2 is a bottom prospective view thereof;

FIG. 3 is a side view thereof;

FIG. 4 is another side view thereof;

FIG. 5 is a prospective view thereof, shown in an alternate position;

FIG. 6 is a side view thereof, shown in an alternate position; and,

FIG. 7 is another side view thereof, shown in an alternate position.
